COLLAPSIBLE BOAT

Clarence R. Jones, Dayton, Ohio

Application December 23, 1946, Serial No. 718,019

13 Claims. (Cl. 9—2)

1

This invention relates to a collapsible boat and is intended primarily for the use of hunters, fishermen, and others who may desire a boat which can be transported in an automobile, or the like.

One object of the invention is to provide a boat of light weight which can be collapsed into a small compact bundle.

A further object of the invention is to provide a telescoping boat which may be quickly and easily extended to its full length and the joints tightly sealed.

A further object of the invention is to provide such a boat the sections of which have inter-engaging parts which are brought into locking and sealing relation by the movement of the sections to their extended positions.

A further object of the invention is to provide such a boat in which interlocking connection between the sections is effected by the movement of the sections to their extended positions.

A further object of the invention is to provide such a boat having extensible means in the individual sections to exert pressure on adjacent sections to secure the sections in extended positions.

Other objects of the invention may appear as the boat is described in detail.

In the accompanying drawings Fig. 1 is a perspective view of a boat embodying the invention; Fig. 2 is a longitudinal section taken through the rear section and the next adjacent section; Fig. 3 is a perspective view showing the boat in its fully collapsed condition; Fig. 4 is a perspective view of the end portions of two adjacent sections showing the same in separated positions; Fig. 5 is a perspective view of the interlocked portions of the side walls of two sections; Fig. 6 is a vertical longitudinal section taken through two adjacent sections; and Fig. 7 is a detail of one of the latches.

In these drawings I have illustrated one embodiment of the invention and have shown the same as comprising a plurality of sections adapted to be collapsed one into the other, and having means whereby the several sections may be locked in their extended positions and tightly sealed. In the present instance the boat comprises four sections, 10, 11, 12, and 13, the side walls of the several sections converging forwardly, the rear end of each forward section being of a width slightly less than the width of the next rearward section to permit it to be moved into said next rearward section, thus enabling all the sections to be telescoped into the rearmost section 10, as shown in Fig. 3. Each section comprises upright

2

side walls 14 and bottom walls 15 which, in the present instance, are substantially flat. The rearmost section 10 is closed at its rear end by an upright wall 16 and the foremost section 13 is closed at its front end by a wall 17, the end walls being preferably formed in one piece with the respective sections. The intermediate sections, 11 and 12, are also formed, respectively, in one piece, thus the several sections may be formed by pressing or otherwise from light weight material such as aluminum or a suitable plastic material. Preferably the sections are formed of relatively thin sheet metal of light weight so that the boat as a whole will be of such a weight that it can be easily handled by one person either in its extended or collapsed form.

The several sections are provided at their adjacent ends with inter-engaging parts which are adapted to be brought into inter-engaging relation when the several sections are extended, and to be rigidly secured and tightly sealed in said inter-engaging positions. Preferably the side walls of each section except the foremost section have their forward portions bent inwardly and rearwardly as shown at 18 to form inwardly and rearwardly facing channels. Likewise each section except the foremost section has at the forward end of its bottom wall 15 an upwardly extending part such as a flange 19. The side walls of each section except the rearmost section have their rear end portions bent outwardly and forwardly as shown at 20 to form outwardly and forwardly facing channels adapted to have interlocking engagement with the channels 18 of the next rearward section. The bottom wall of each section except the rearmost section has at its rear end an upwardly and downwardly bent portion 21 to form a downwardly facing channel adapted to receive the flange 19 at the forward end of the bottom of the next rearward section. When the several sections are extended from the collapsed position shown in Fig. 3 the outwardly extending channel portions of the forward sections engage the inner sides of the converging walls of the adjacent rearward sections and are guided into engagement with the inwardly facing channel portions of said rearward sections, thus positively connecting the several sections, the several sections being retained in these extended positions as will hereinafter appear.

Arranged between the interlocking portions of the respective sections is a suitable sealing medium and preferably the channels are lined with a relatively thick liner of a compressible sealing material 22, such as sponge rubber. Either or

both of the upright channels of the side walls may be provided with this lining material.

Means are provided for locking the several sections in their extended positions and for compressing the sealing medium in the several joints. For this purpose I prefer to provide a separate extensible device in each section adapted to be interposed between fixed parts of that section and an adjacent section. In the present construction this extensible device is in the nature of a floor board comprising two parts, 23 and 24, hinged one to the other at 25 for movement about a transverse horizontal axis and adapted to have a toggle action. The floor board is removable and foldable for transportation and storage. When the sections have been extended the floor board is inserted in the section in which it belongs with the two parts, 23 and 24, thereof inclined upwardly toward the hinge. In this position the part 23 is placed in engagement with a rigid part of the section and the part 24 is placed in engagement with the rigid part of an adjacent section so that when the central portion of the floor board is depressed to a horizontal position pressure will be exerted in opposite directions on the respective sections as to lock those sections in their extended positions and to compress the sealing medium. In the particular arrangement shown the part 23 of the floor board in the rearmost section 10 engages the rear wall 16 of that section, and the part 24 of the floor board engages the raised or channel-shaped portion of the next forward section. The floor board is preferably of a width approximating the width of the section in which it is placed but it may be of any desired width. Suitable means are provided for locking the two parts of the floor board in their horizontal positions and this means is here shown as a latch 26 pivotally mounted on the member 23 and adapted to engage a headed stud 27 on the part 24. It is also desirable that means should be provided for securing the floor board to the bottom of the boat. In the arrangement shown the floor board is spaced above the bottom of the boat section, as by depending ribs 28, and is provided at its ends with relatively thick portions 29 and 30 to engage the respective fixed parts of the two sections. The rear wall of the rearmost section 10 is provided with one or more forwardly extending flanges, or lugs 31, beneath which the rear end of the floor board is inserted. The forward end of the floor board is connected with the bottom of the section by a latch carried by the forward portion of the floor board and adapted to engage a keeper on the bottom of the section. As here shown the keeper is in the nature of an apertured lug 32 rigidly secured to the bottom, and the latch comprises a horizontal portion 33 adapted to enter the keeper and an upwardly extending part 34 having a head 35 slidably supported on the part 24 of the floor board, which is provided with a slot 36 through which the upright part of the latch extends and which is provided with a shoulder 37 on which the head 35 is slidably supported. Thus the latch can be easily actuated from above the floor board to connect the latter with or disconnect the same from the bottom of the section. If desired the forward end of one floor board may be provided with a recess 38 adapted to receive a stud 39 extending rearwardly from the floor board in the adjacent section and thus so position the part 24 of the floor board that the latch will be in alignment with the keeper. The rear end of each floor board in front of the rearmost floor board en-

gages the raised portion 21 of the section in which it is mounted and is locked to the bottom of its section by connecting it with the forward end of the next rearward floor board. The locking means shown comprises a casing 40 rigidly secured to the rear end of the forward floor board and having mounted therein a slide bolt 41 adapted to be projected beyond the rear end of that floor board and into a keeper or keepers 42 at the forward end of the next rearward floor board. The forward thrust on the several sections will maintain the sealing medium firmly compressed but to prevent the relative displacement of the upright channelled portions 18 and 20, as by the bending of one or both of the side walls, I have shown the same as provided with apertures to receive bolts 43 which are preferably provided with thumb nuts, 44.

The boat may if desired be provided with oar locks but usually such a boat will be propelled by a paddle. The rearmost section may be provided with a seat, and as shown in Fig. 1 the seat 45 is removably supported on brackets 46 secured to the inner sides of the side and rear walls of the rear section.

A boat constructed in accordance with the disclosure is of light weight, can be very quickly and easily collapsed into a small bundle which can be easily carried in a passenger automobile, and when extended is of a strong rigid construction, and the joints thereof are tightly sealed. When the boat is to be collapsed the rear ends of the several sections are successively lifted to clear the flanges on the rearward sections and thus permit each forward section to be moved into the next rearward section until all the forward sections are in the rearmost section. When the boat is to be extended the foremost section is drawn forwardly and causes each of the intermediate sections to be drawn forwardly until the bottom channels drop into engagement with the respective flanges 19, and the side channels are in interlocking engagement. The floor boards are then placed in the respective sections and extended to lock and seal the connections between the sections. The floor board for the front section has no locking action but is placed within the section, which is provided with a lug or bracket 47 to overhang the forward end thereof and retain it in place.

While I have shown and described one embodiment of my invention, I wish it to be understood that I do not desire to be limited to the details thereof as various modifications may occur to a person skilled in the art.

Having now fully described my invention, what I claim as new and desire to secure by Letters Patent is:

1. A collapsible boat comprising a plurality of transverse sections each having bottom and side walls, each forward section being movable into engagement with the adjacent rearward section, the bottom and side walls of adjacent sections having opposed parts arranged to have interlocking connection when the forward section is fully extended, sealing means between said interlocking parts, and separately operable extensible devices supported between opposed parts of the sections of each pair of adjacent sections to move the respective sections in opposite directions and firmly connect and tightly seal the same.

2. A collapsible boat comprising a plurality of telescoping sections, each section having bottom and side walls, the bottom wall of one of two

adjacent sections having at the forward end thereof an upwardly extending flange and the side walls of said section having forward end portions thereof turned inwardly and rearwardly to form rearwardly facing channels, the bottom wall of the second of said adjacent sections having adjacent its rear end a downwardly facing channel to receive the flange on the first mentioned bottom wall, and the side walls of said second section having their rear ends turned outwardly and forwardly to enter the channels in the first mentioned side walls, sealing means in said channels, and means within one of said adjacent sections to exert pressure on the two sections in opposite directions to compress said sealing means.

3. A collapsible boat comprising a plurality of telescoping sections each having bottom and side walls, adjacent sections having at their adjacent ends interlocking parts to connect said sections in their extended positions, sealing means between said interlocking parts, and extensible means removably supported in one section of each pair of adjacent sections to engage opposed parts of the two sections of said pair and exert pressure thereon in opposite directions.

4. A collapsible boat comprising a plurality of telescoping sections each having bottom and side walls, adjacent sections having at their adjacent ends interlocking parts to connect said sections in their extended positions, sealing means between said interlocking parts, and separately operable extensible devices interposed between the two sections of the respective pairs of adjacent sections, each device comprising two parts hinged one to the other and adapted to engage opposed portions of said adjacent sections and of such length that when said parts are moved into alignment they will press the interlocking parts of said sections into tight sealing relation one to the other.

5. A collapsible boat comprising a plurality of telescoping sections each having bottom and side walls, adjacent sections having at their adjacent ends interlocking parts to connect said sections in their extended positions, sealing means between said interlocking parts, and separately operable extensible devices removably supported between the two sections of the respective pairs of adjacent sections, each device comprising two parts hinged one to the other and adapted to engage opposed portions of said adjacent sections and of such length that when said parts are moved into alignment they will press the interlocking parts of said sections into tight sealing relation one to the other.

6. A collapsible boat comprising a plurality of telescoping sections each having bottom and side walls, adjacent sections having at their adjacent ends interlocking parts to connect said sections in their extended positions, and floor boards for the respective sections, each comprising two members hinged one to the other and of a width approximating the width of said section, said floor board when flexed being engageable with opposed parts of said adjacent sections and being of such length that the movement of said members into a common plane will secure said interlocking parts in sealing relation one to the other.

7. A collapsible boat comprising a plurality of telescoping sections each having bottom and side walls, adjacent sections having at their adjacent ends interlocking parts to connect said sections in their extended positions, sealing means be-

tween said interlocking parts, separately operable extensible devices interposed between the two sections of the respective pairs of adjacent sections, each device comprising two parts hinged one to the other and adapted to engage opposed portions of said adjacent sections and of such length that when said parts are moved into alignment they will press the interlocking parts of said sections into tight sealing relation one to the other, and means for locking said parts of said device against relatively pivotal movement.

8. A collapsible boat comprising a plurality of telescoping sections each having bottom and side walls, adjacent sections having at their adjacent ends interlocking parts to connect said sections in their extended positions, and removable floor boards for the respective sections, each comprising two members hinged one to the other and of a width approximating the width of said section, said floor board when flexed being engageable with opposed parts of said adjacent sections and being of such length that the movement of said members into a common plane will secure said interlocking parts in sealing relation one to the other, and releasable means for preventing the upward movement of said floor board with relation to the section in which it is mounted.

9. A collapsible boat comprising a plurality of telescoping sections each having bottom and side walls, adjacent sections having at their adjacent ends interlocking parts to connect said sections in their extended positions, sealing means between said interlocking parts, a device removably supported between two of said sections and comprising two parts hinged one to the other and adapted to engage opposed portions of said sections and of such length that when said parts are moved into alignment they will press the interlocking parts of said sections into tight sealing relation one to the other, means for locking said parts of said device against relatively pivotal movement, and inter-engaging parts permanently secured respectively to said device and to the bottom wall of said section to prevent the upward movement of said device, one of said parts being operable from above said device to engage and disengage the same from the other of said parts.

10. A collapsible boat comprising a plurality of telescoping sections each having bottom and side walls the side walls of adjacent sections having end portions movable into interlocking engagement one with the other, the bottom wall of each of two adjacent sections having at one end an upwardly extending flange and having at its other end a raised portion having a downwardly facing channel to receive the flange of an adjacent section, a floor board for one of said sections comprising two parts hinged one to the other on an axis transverse to the boat, and having front and rear end portions to engage respectively the raised portions of the bottom walls of the section in which it is located and of an adjacent section, and to exert pressure thereon when said parts of said floor board are in a common plane.

11. A collapsible boat comprising an elongate body divided transversely into a plurality of sections, each section having a bottom wall and upright side walls, and the front and rear sections having respectively a front wall and a rear wall, said sections decreasing in width progressively from one end of said body to the other end thereof to enable each smaller section to

be moved longitudinally into the adjacent larger section, the bottom and side walls of adjacent sections having at the adjacent ends thereof opposed parts arranged to have interlocking engagement when said sections are fully extended, sealing means between said interlocking parts, and means for exerting pressure on two of said sections in opposite directions to fully extend said sections.

12. A collapsible boat comprising an elongate body divided transversely into a plurality of sections, each section having a bottom wall and upright side walls, and the front and rear sections having respectively a front wall and a rear wall, said sections decreasing in width progressively from one end of said body to the other end thereof to enable each smaller section to be moved longitudinally into the adjacent larger section, the bottom and side walls of adjacent sections having at the adjacent ends thereof opposed parts arranged to have interlocking engagement when said sections are fully extended, sealing means between said interlocking parts, and toggle means interposed between and engaging two of said sections to move the latter 25 in opposite directions, said toggle means being unattached to said sections and removable therefrom when moved to section releasing position.

13. A collapsible boat comprising an elongate body divided transversely into a plurality of sections, each section having a bottom wall and upright side walls, and the front and rear sections having respectively a front wall and a rear wall, said sections decreasing in width progressively from one end of said body to the other 30 35

end thereof to enable each smaller section to be moved longitudinally into the adjacent larger section, the bottom and side walls of adjacent sections having at the adjacent ends thereof opposed parts arranged to have interlocking engagement when said sections are fully extended, sealing means between said interlocking parts, and a floor board having members hinged one to the other on an axis transverse to said body and adapted to be interposed between opposed parts of two of said sections, said members being movable longitudinally of said body with relation to said sections and of such dimensions that when moved into a common plane they will have 15 abutting engagement with said opposed parts of said sections and exert pressure thereon in opposite directions to establish rigid sealed connection between said sections.
